SILENCER

John A. Day, Madison, Wis., assignor to C. F. Burgess Laboratories, Inc., Madison, Wis., a corporation of Delaware

Application November 11, 1932, Serial No. 642,152

2 Claims. (Cl. 137—160)

This invention relates to a silencer for internal combustion engines and more particularly to improvements in silencers of the type disclosed in United States patent to F. H. Schnell, No. 5 1,811,762, granted June 23, 1931:

The silencer forming the subject matter of the present application is particularly adapted for the silencing of carburetor intakes. It comprises a silencer which is highly efficient for this purpose, and which occupies a minimum of space. It is also adapted to have an air filter incorporated with it without adding appreciably to its size. The silencer of my invention offers a minimum of resistance to the flow of air therethrough.

It is also designed to provide a silencer which is particularly adapted for use with down-draft carburetors and which, even in the absence of a filter, minimizes the entrance of particles of dirt and dust into the carburetor with the air stream.

In the accompanying drawing, several forms of the invention are illustrated. In the drawing,

Fig. 1 is a longitudinal, sectional view of one form of my improved silencer;

Fig. 2 is a partial transverse view of the silencer shown in Fig. 1;

Fig. 3 is a longitudinal, sectional view of the silencer with an air filter attached;

Fig. 4 is a transverse or front view of the combination shown in Fig. 3;

Fig. 5 is a longitudinal, sectional view of a modification of the invention with the filtering unit incorporated therein in such a way as not to increase its size; and

Fig. 6 is a front view of the silencer shown in Fig. 5.

In Fig. 1, the outer shell of the silencer comprises a concave substantially bowl-shaped member 10, preferably formed of sheet metal. A similarly shaped foraminous member 11 is disposed interiorly of the shell 10 in spaced relation thereto. The inner member 11 is supported by engagement of the two members at their peripheries. Inner shell 11 is preferably drawn from a single piece of perforated sheet metal. In the space between the two members a filling 12 is arranged. The filling 12 comprises porous-packed material capable of absorbing sounds and gas-pressure-pulses, and may be termed briefly a gaseous pressure-wave absorbing material. It may be wool, cotton or other cellulosic fibers, mineral wool, steel, copper or other metallic wool or mixtures thereof, exfoliated ver-

miculite or other materials mentioned in the said Schnell patent.

A substantially flat annular plate 13 is arranged over the silencer and is attached at its outer periphery to the periphery of outer shell 10. Plate 13 and inner shell 11 may be attached to outer shell 10 by forming a radially outwardly extending bead 19 in outer shell 10 and crimping the marginal portion of the latter over the edges of plate 13 and inner shell 11. The attachment 10 may be reinforced by spot welding at desired points. Plate 13 has a plurality of openings 14 (see Fig. 2) arranged radially about its axis and spaced inwardly from its outer periphery. These openings may be elongated circumferentially as 15 shown. A rather short section 15 of a cylinder is attached intermediate between its ends to the inner periphery of plate 13. Cylinder section 15 may be secured to the plate 13 by any suitable means such as spot welding. The portion of cylinder 15 located interiorly of plate 13 preferably is foraminous.

An annular convex or ring-shaped sheet metal member 16 is secured, as by means of spot welding, to the inner side of plate 13 and spaced from the inner shell 11 to form an air passage. Annular member 16 is foraminous and is substantially U-shaped in transverse section. Its inner end is secured to the central cylinder member 15. Like inner shell 11, annular member 16 is preferably drawn from a single piece of perforated, smooth-surfaced sheet metal. Plate 13, cylinder 15 and member 16 unite to form a closed annular shell, substantially D-shaped in transverse section. A filling 17 of a gaseous pressure-wave absorbing material may be disposed within this shell. The foraminous walls of the annular D-shaped member and inner shell 11 may have interior linings 20 of cheese cloth. Openings 14 are arranged to register with the passage between the inner shell 11 and annular member 16. The exterior portion of cylinder 15 is adapted to fit over the carburetor intake and may be held in place by means of clamp 18.

In operation openings 14 form the entrance 46 openings for incoming air and the space between annular member 16 and inner shell 11 forms the air passage from the entrance to the interior end of cylinder 15. An annular passage is thus provided for the air which converges smoothly 50 and without angularity and unites in continuous fashion with a centrally disposed, oppositely directed circular passage through cylinder 15.

The circular passage connects directly with the carburetor. A passage-way is thus provided 55

through the silencer which is lined substantially throughout its length with a gaseous pressure-wave absorbing material. Any sounds emerging from the carburetor, caused by the rush of air or the operation of valves, are silenced and any gas pulses caused by sudden changes of flow conditions are absorbed.

For instance, it is known that when an intake valve is suddenly closed in the face of a rapidly moving stream of air momentary compression of the air stream occurs at the valve and this compression travels backwardly through the conduit or system in the form of a gas pressure pulse which creates a noise upon its emergence from the system. Any such pulses which travel backwardly through the carburetor are absorbed in the porous linings of the silencer duct.

One of the important advantages of my improved intake silencer lies in the fact that it offers practically no resistance to the flow of air therethrough. Any resistance to air flow, of course, reduces the efficiency of the engine. The passage-way through the silencer is of a minimum length and the walls are of continuous smooth-surfaced perforated metal. Such surfaces offer practically no more resistance to the flow of a gas stream than do smooth, non-perforated metal surfaces. In the drawing operation upon the perforated sheet metal, at those points where increased curvature occurs, the perforations may become distorted into the form of more or less narrow slits but this does not impair the efficiency of their cooperation with the gaseous pressure-wave absorbing material for suppressing noises. The walls are arranged to avoid excessive non-uniformity of cross sectional duct area with length and to avoid abrupt or angular direction changes which factors cooperate to prevent the building up of eddy currents which would otherwise interfere with and obstruct the free flow of the air stream.

Another advantage of my silencer lies in the fact that when it fits over the vertical intake of a down-draft carburetor, concave member 10 forms a covering and protection against dust and dirt particles that might otherwise drop into the carburetor intake. Furthermore, the entering air passes into the silencer in an upward direction so that the heavier dirt particles may be dropped from it before it enters.

If it is desired to incorporate an air filter with the silencer a device similar to that illustrated in Figs. 3 and 4 may be attached over the entrance of the silencer. The device comprises an annular sheet metal shell 21 which may have its side walls 22 project rearwardly beyond its rear wall 23. Spring clips 24 are attached at suitable circumferential intervals around the outer side wall 22 and these clips are adapted to snap over bead 19 to hold the filter in place. An annular forwardly projecting bead 25 may be formed on plate 13 and the rear marginal portions of inner side wall 22 may be arranged to fit over bead 25. Annular combination gaskets and cushioning members 26 of rubber or other compressible elastic material may be arranged between the filter and plate 23. Openings 27 may be provided in front and rear walls 23 and these openings may be provided with coarse mesh screen coverings 28. Coverings 28 may be formed by attaching annular sheets of screen to the interior surfaces of front and rear walls 23. Shell 21 may be filled with filtering material 29 which is preferably a mass of fine copper wire having a coating of tacky material, for example, an oil of such viscosity that a thin

film clings to the wire strands. Filtering material 29 also assists the silencer by absorbing sounds which reach it.

A majority of openings 27 communicate with openings 14 in plate 13. Gaskets 26 serve to prevent the entrance of air around the rear edges of side walls 22 and insure that all air passes through the filtering material. They also prevent relative motion between the two units and any consequent rattling.

Figs. 5 and 6 illustrate a modification of my silencer in which the filtering unit is adapted to be incorporated in the gas passage thereof without resulting in any increase in the size of the silencer. Outer concave shell 31 is similar in all respects to shell 10 except that it is provided with a central opening 32. A foraminous concave inner shell 33 is attached to outer shell 31 at its periphery. Inner shell 33 has its central portion deformed outwardly into contact with outer shell 31. It is also provided with a central opening 34 and has an annular indentation 35 impressed upon it at its intermediate portion. A closed hollow annular shell 36, substantially D-shaped in transverse section, is supported within inner shell 33 in spaced relation thereto. Annular shell 36 carries an annular plate 37. The inner periphery of plate 37 is secured to a cylinder 38 similar to cylinder 15, and its outer periphery is secured to a U-shaped member 39 similar to annular member 16. A bracket 40 is arranged in the air passage, and its ends are secured to the top of U-shaped member 39. Its intermediate portion extends upwardly and its mid-portion abuts the central portion of inner shell 33. The central portion of bracket 40 has opening 41 therein. Bolt 42 threads openings 32, 34, and 41 and when nut 43 is drawn up tightly upon bolt 42 the assembly is fastened rigidly together and annular shell 36 is held in place. Bolt 42 may be spot-welded to bracket 40. The relation of the parts is substantially the same as that of the silencer shown in Fig. 1.

Tongues 45 and 46 project radially outward from the peripheries of member 39 and plate 37, respectively, and are spaced circumferentially desired distances apart. These tongues may be welded together to form the attachment between member 39 and plate 37. The end portions of tongues 46 may be turned rearwardly substantially at right angles to form a plurality of retaining ledges. A cylindrical filtering unit 47 of fine mesh wire may be inserted within the space between member 39 and inner shell 33 with one edge resting against indentation 35 and the other edge resting within tongues 46.

Filtering unit 47 may be of tinned steel wire having an adherent tacky coating of oil as described in connection with filtering material 17 shown in Fig. 1. Filtering unit 47 is, in this manner, incorporated within and interposed across the air passage of the silencer and no increase in silencer size is made necessary by its presence.

Annular member 36 and the space between concave shells 31 and 33 may be filled with fillings 48 and 49, respectively, of gaseous pressure-wave absorbing material. The path of the air is substantially the same as that in the silencer illustrated in Fig. 1. Bracket 40 does not obstruct the flow of air to any appreciable extent.

I claim:

1. A silencer comprising a double walled, concave member, the inner wall being foraminous and the space between said walls being filled

with sound-absorbing material, an annular plate having a plurality of spaced openings therein attached to the edge of said concave member, a hollow foraminous annular member attached to said plate and disposed interiorly of and spaced from said concave member, said annular member having a central opening registering with a central opening in said plate, said annular member being filled with sound-absorbing material, said inner central openings of said plate and said annular member respectively, and the space between said members forming a continuous gas passage for said silencer, said spaced openings in said plate registering with said gas passage.

15 2. A silencer comprising a double-walled, concave member, the inner wall being of shaped perforated sheet metal and the space between said walls being filled with gaseous pressure-

wave absorbing material, a flat annular plate attached to the edge of said concave member and having openings adjacent its outer periphery, a cylinder passing through said plate toward said concave member, and a hollow annular member 5 of shaped perforated sheet metal substantially U-shaped in transverse section attached to said plate and said cylinder respectively and disposed interiorly of said concave member with its convex surface adjacent to and spaced from said concave member, said annular member being filled with gaseous pressure-wave absorbing material, said cylinder and the space between said members forming a continuous gas passage, said openings in said plate registering with said gas 10 passage.

JOHN A. DAY.
